CARBURETER APPARATUS FOR INTERNAL-COMBUSTION ENGINES.

1,240,440.

Specification of Letters Patent. Patented Sept. 18, 1917.

Application filed August 8, 1916. Serial No. 113,700.

To all whom it may concern:

Be it known that I, WILLIAM GRIKSCHET, a citizen of the United States, and resident of Detroit, in the county of Wayne and 5 State of Michigan, formerly of New York, in the county and State of New York, have invented certain new and useful Improvements in Carbureter Apparatus for Internal-Combustion Engines, of which the following 10 is a specification.

This invention relates to a carbureter apparatus for internal combustion engines, and it has for its object to provide means whereby heavy fuel oil, such as kerosene, can be 15 utilized for the production of an explosive mixture of high efficiency in respect of economy, power and flexibility of operation.

According to the principle of my invention I mix atmospheric air with a heavy 20 liquid hydrocarbon and heat the mixture in such a manner as to produce a superheated vapor which is so rich in hydrocarbon that it cannot be ignited; and I then cool (but do not condense) the vapor and variably 25 supply artificially-humidified air thereto in response to the variations in the speed of the engine to which the invention is applied.

In the form of embodiment of my invention herein illustrated I employ a carbureter whereby a rich mixture of oil and air is secured; a heating structure into which the mixture is delivered and therein converted into superheated vapor, and a relatively long conduit through which the 35 vapor is conducted from said structure to a point where humidified air is mixed therewith, the vapor in its prolonged passage, preparatory to the admixture of the humidified air therewith, being appreciably cooled, 40 but not condensed, thereby insuring the production of an explosive mixture of high efficiency.

The invention also comprises various features of construction and combinations of 45 parts whereby advantages are gained, all of which will be hereinafter described and claimed.

In the drawings—

Figure 1 is a side elevation of a carbureter 50 apparatus embodying the principle of my invention.

Fig. 2 is a plan of the heating structure and adjuncts, part of the body being broken away to show internal passages.

Fig. 3 is a longitudinal vertical section, as 55 on the line 3—3 of Fig. 2.

Fig. 4 is a transverse section, as on the line 4—4 of Fig. 2.

Fig. 5 is a similar section, partly in elevation, of the air-humidifying structure and 60 its connections with the conduit from the heating structure; showing the gasoline carbureter in section.

Fig. 6 is a plan of the humidifying structure, parts being broken away for clearness. 65

Referring to the drawings, 10 designates a carbureter or analogous structure by means of which an admixture of air and oil, such as kerosene, is effected. This carbureter in the form illustrated includes a vertically- 70 movable venturi 11 communicating at its lower end with the atmosphere, and an oil nozzle 12 projecting centrally into the lower restricted portion of the venturi and operatively connected with the float chamber 13 75 comprising the carbureter body. The annular air inlet encircling the tip of the nozzle is so proportioned relatively to the bore of the nozzle that in the operation of the engine the quantity of air drawn into the venturi is small compared with the quantity of oil carried from the nozzle by the inrushing air current. The nozzle outlet is provided with a needle valve 14 which is connected with the venturi so that as the latter is more 80 or less lifted in response to the variations in speed of the engine, the valve is actuated to adjust automatically the area of the outlet and thus proportionately regulate the delivery of oil to the venturi. 90

The neck of the carbureter is connected to a heating structure having a retort or chamber 15 which is adequately heated by the exhaust gases from the engine. The venturi is in open communication with the 95 chamber 15 in order that the very rich mixture of oil and air, as rapidly as it is produced, will be delivered to said chamber and therein converted into a superheated vapor having a relatively high temperature. This 100 vapor is so rich in hydrocarbon that it cannot be ignited.

The form of heating structure herein illustrated comprises an elongated hollow body 16 having at its respective ends an inlet and 105 an outlet for the exhaust gases from the engine. The inlet is connected with the exhaust gas pipe 17 from the engine, and the

outlet is provided with a discharge pipe 18. The pipe 17 opens into and forms, in effect, a continuation of a flue 19 which extends within and longitudinally of the heating chamber, said flue being so constructed and proportioned in respect to the heating chamber that the mixture of air and oil from the carbureter 10 may be introduced into one end of said chamber and permitted to flow in a prolonged course therethrough in contact with the wall of the flue for the efficient production of the superheated vapor preparatory to its discharge at the end of the structure adjacent the flue inlet. The inner 15 end of the flue communicates by way of spaced passages 20 with a chamber 21 in valved communication with the outlet for the exhaust gases. This chamber 21 opens directly into one end of a flue 22 which ex- 20 tends beneath and longitudinally of the heating chamber 15, and communicates at its opposite end with a return flue 23 leading to and communicating with the exhaust gas outlet, as at 24. This outlet is pro- 25 vided with a suitable valve 25, such as the butterfly type shown, which is so disposed that it may be operated to close or open the direct communication between the chamber 21 and the outlet. When the valve 25 is 30 closed, the exhaust gases entering the chamber 21 are diverted therefrom to the flue 22 through which they flow in close contact with and longitudinally of the lower wall of the heating chamber, thence into the 35 return flue 23 and thence to the open outlet. When, however, the valve 25 is opened, the exhaust gases flow directly from the chamber 21 to the adjacent outlet, thus mate- 40 rially reducing the quantity of available heat in the heating chamber.

In pursuance of one feature of my invention thermostatic means is provided whereby the valve is automatically controlled in response to the varying requirements; that is to say, when the heat of the heating structure exceeds a predetermined temperature the valve is opened to permit the direct flow of the exhaust gases to the discharge pipe 18, and then, on the other hand, when the temperature of such structure falls to or below the prescribed limit, the valve is closed in order to permit the prolonged flow of the exhaust gases in contact with the wall of the heating chamber. 55 Any appropriate thermostatic means may be employed. The form shown includes a casing 26 suitably supported on the external wall of the heating structure, and metallic thermal members 27 arranged within 60 the casing and successively connected with levers 28. The final member projects through the bottom of the casing and contacts with a set-screw 29 on one arm of a suitably-disposed lever 30, the other arm of 65 which is connected by means of a link 31

with a crank arm 32 on the pivot stud of the valve 25. A spring 33 secured to the latter arm of the lever and to an adjacent projection on the wall of the casing tends to maintain the valve normally closed. It 70 will be seen that during the contraction and expansion of the thermal members in response to the varying temperatures of the heating structure the lever is automatically actuated in a manner to open or close the 75 valve.

The superheated vapor evolved in the heating chamber 15 flows into and through a long conduit 34 which is suitably connected with the manifold 35 of the engine, 80 the connections including a throttle valve 36 of any ordinary or approved type by the manual operation of which the supply of the charge to the engine can be controlled. This conduit 34 is provided at a suitable 85 point between the heating structure and the throttle valve with an air-inlet connection 37 with which is operatively connected an air-supply pipe 38. The connection is preferably equipped with a spring-loaded pup- 90 pet valve 39 which normally closes the inlet, but is retracted to open the latter during the intake strokes of the engine piston or pistons. The air inlet is located at a point sufficiently remote from the heating struc- 95 ture to permit the appreciable cooling of the rich vapor preliminary to the admixture of humidified air therewith; the tempera- 100 ture being such that no condensation of the vapor takes place, and therefore there is no liability of deposition of oil in the conduit. In the present instance the cooling conduit is exposed to the atmosphere and air currents and is of sufficient length and has sufficient cooling surface to insure the re- 105 quisite cooling of the vapor in its passage therethrough from the heating structure to the air inlet, the fall in vapor temperature ranging from 30° to 70° F., more or less, according to the temperature of the super- 110 heated vapor when it enters the conduit. The conduit constituting the cooling means for the superheated vapor may, of course, be coiled, water jacketed or otherwise ap- 115 propriately constructed to provide the re- quisite cooling surface whereby the vapor is adequately cooled without condensation preparatory to the admixture of the hu- 120 midified air therewith. The volume of air delivered to the vapor greatly exceeds that supplied to the oil at the carbureter 10, such larger volume of air being uniformly moistened before its admixture with the vapor in order to produce an explosive mixture having a high percentage of relative 125 humidity. The cooling of the superheated vapor before the admixture of the humidified air therewith not only facilitates the efficient humidification of the vapor, but it also insures the admission to the cylinder 130

of increased weight or density of the explosive mixture with correspondingly increased power. The introduction of the larger quantity of humidified air has the important practical effect of maintaining a relatively constant temperature of the mixture entering the engine, thereby insuring uniform operation and flexibility of control. Moreover carbonization in the cylinders and their immediate connections is minimized. The cooling of the superheated vapor preparatory to the admixture of humidified air therewith is an important feature of my invention, and I, therefore, wish to emphasize the same.

It is to be noted that the heating chamber is preliminarily heated to the proper temperature by the initial operation of the engine through the medium of an explosive mixture of a lighter fuel, as gasolene, and air. Accordingly a carbureter 40 for the lighter fuel is operatively positioned adjacent the throttle and manifold connections, and the passage of the mixture from said carbureter 40 for delivery to the manifold, is controlled by a suitable valve 41 which may be manually or otherwise operated. (See Fig. 5.)

An important feature of my invention is that the air which is introduced to the vapor flowing from the heating chamber is always maintained at or near the point of saturation, irrespective of load. Furthermore by the operation of the suction-controlled inlet valve 39 the humidified air is variably supplied to the vapor in response to variations in the speed of the engine.

A typical means for humidifying the air is herein illustrated and will now be described. Referring to Figs. 5 and 6, 42 designates a casing, rectangular in cross-section, adapted to contain within its lower portion a body of water. This casing is provided with a suitable overflow 43 to determine the water level, and it is also provided with a cover plate 44 through which extends adjacent to one corner thereof the elongated vertical limb 45 of a U-shaped air-inlet pipe which depends to or near to the bottom of the casing diagonally thereof. The other vertical member 46 rises to a level somewhat below the cover-plate and its wall is provided with a multiplicity of perforations 47 throughout the greater part of its length, as shown. The wall of the lower cross-member 48 of the air-inlet pipe is also provided with a series of rows of small perforations 49.

Depending into the casing to a plane somewhat above the level of the water is an outlet pipe 50 which is connected at its upper end to the air-supply pipe 38 leading to the air-inlet connection 37 of the conduit; the wall of the pipe 50 being perforated throughout a considerable portion of its

length, as at 51. Within the casing, between the foot of the pipe 50 and the head of the vertical pipe member 46, is a series of horizontal partitions comprising perforated plates 52 arranged in spaced relation to each other. In the present instance four partitions are employed, the opposite ends of alternate partitions being spaced from the adjacent walls of the casing so as to afford communication between the successive chambers and provide an extended passage for air entering the uppermost chamber from the pipe member 46 and flowing to the foot of the outlet pipe 50 in the lowermost chamber, as indicated by the arrows. The floor of the latter chamber comprises a plate 53 which declines slightly from the wall of the casing at a point below the pipe 50 to the opposite wall of the casing, adjacent to which the floor is preferably provided with an opening having a depending drain pipe 54. The perforated partition plates 52 and the floor plate 53 are covered with felt 55, or other suitable absorbent material, and the perforated limbs of the inlet and outlet pipes respectively, together with the under side of the cover plate of the casing are similarly covered, as shown in Fig. 5.

By the construction and arrangement of parts just described in respect of the air-humidifying structure, it is to be noted that when the motor is idle the water within the casing percolates through the absorbent material about the pipe 45 and then through the perforations 49, filling the tube 45, 46 with water up to the level of the over-flow pipe 43. When the motor is started atmospheric air enters the open mouth of the inlet pipe member 45 during the intake strokes of the engine, which air displaces the volume of water in the pipe and splashes it into and through successive chambers of the casing. Part of the water is deposited within the uppermost chamber and part escapes through the perforations of the pipe member 46, thereby wetting the contiguous bodies of felt. The water percolates through the felt in the uppermost chamber and through the perforated partition, and thus it passes from chamber to chamber and is progressively taken up by the opposing absorbent material. Thereafter during the operation of the motor the air passes through the devious felt-lined passages within the casing to the outlet pipe 50 and thence to and through the pipe 38 leading to the valved inlet to the cooling conduit. The water within the casing is drawn in a mist or spray into the air-inlet pipe through the felt-covered perforated cross member 48 and thence within the perforated pipe member 46 by the variable air pressure. Part of the water is deposited within the uppermost chamber of the casing and part escapes through the perforations of the pipe member 46, thereby in-

suring the continued saturation of the contiguous bodies of felt. The water seeps through the felt in the uppermost chamber and through the perforated partition, and thus in a mist or finely atomized condition it passes from chamber to chamber until it reaches the covered floor 53 whence water passes to the drain pipe 54.

The air in its devious course through the successive chambers draws more or less water-vapor through the perforations of the respective pipes, thus freely distributing the water-vapor among the absorbent coverings and bringing the impinging air to or near to the point of saturation before its escape from the casing. Hence the humidified air when it is delivered to the cooling conduit is approximately saturated, irrespective of the load of the engine, and as a result the diffusion of the humidified air with the vapor is rapidly effected, and a homogeneous explosive mixture of high efficiency is obtained.

I preferably provide the top of the humidifier casing with a series of air-inlets 56 and a rotary regulating valve 57 therefor, whereby the admission of additional air to the casing can, if desired, be had in order to avoid the possible production within such casing of a vacuum of too high degree during the working of the engine.

It is to be understood that the invention forming the subject of the present application is not limited to the specific constructions shown and described, as the elements may be variously modified without departing from the principle of my invention as defined in the appended claims. Furthermore, that the carbureter, the heater, and the air humidifier, separately considered, embody various novel structural features which will form the subjects of separate applications for patents.

What I now claim is—

45 1. In a carbureter apparatus for internal combustion engines, means for mixing air and fuel; means for receiving said mixture and converting it into superheated vapor; means for receiving the said superheated vapor and reducing the temperature thereof, and means for supplying a relatively large proportion of artificially humidified air to the cooled vapor.

55 2. In a carbureter apparatus for internal combustion engines, means for mixing air and fuel; means for receiving said mixture and converting it into superheated vapor; means for receiving the said superheated vapor and reducing the temperature thereof, and means for supplying a relatively large proportion of artificially humidified air to the cooled vapor, said air-supplying means including a valve for automatically controlling the flow of the humidified air.

65 3. In a carbureter apparatus for internal

combustion engines, means for mixing air and fuel; a structure comprising a chamber for receiving said mixture and converting it into superheated vapor; means for maintaining said chamber at a predetermined temperature; means for receiving the said superheated vapor and reducing the temperature thereof, and means for supplying a relatively-large proportion of artificially humidified air to the cooled vapor.

4. In a carbureter apparatus for internal combustion engines, means for mixing air and fuel; a structure comprising a chamber for receiving said mixture and converting it into superheated vapor; means for maintaining said chamber at a predetermined temperature; means for receiving the said superheated vapor and reducing the temperature thereof, and means for supplying a relatively-large proportion of artificially humidified air to the cooled vapor, said air-supplying means including a valve for automatically controlling the flow of the humidified air.

5. In a carbureter apparatus for internal combustion engines, means for mixing air and fuel; means for receiving said mixture and converting it into superheated vapor; a conduit leading from said latter means, and means for supplying artificially humidified air to the conduit at a point sufficiently remote from the vaporizing means whereby the superheated vapor in its passage through said conduit is partially cooled, but not condensed, before the admixture of the humidified air therewith.

6. In a carbureter apparatus for internal combustion engines, means for mixing air and fuel; means for receiving said mixture and converting it into superheated vapor; a conduit leading from said latter means, and means for supplying artificially humidified air to the conduit at a point sufficiently remote from the vaporizing means whereby the superheated vapor in its passage through said conduit is partially cooled, but not condensed, before the admixture of the humidified air therewith, said air supplying means including a valve for automatically controlling the admission of the humidified air to said conduit.

7. In a carbureter apparatus for internal combustion engines, means for mixing air and fuel; a structure comprising a chamber for receiving the mixture and converting it into superheated vapor; means for maintaining said chamber at a predetermined temperature; a conduit leading from the said chamber, and means for supplying artificially humidified air to the conduit at a point sufficiently remote from said chamber whereby the superheated vapor in its passage through said conduit is partially cooled, but not condensed, before the admixture of the humidified air therewith.

8. In a carbureter apparatus for internal combustion engines, means for mixing air and fuel; a structure comprising a chamber for receiving the mixture and converting it into superheated vapor; means for maintaining said chamber at a predetermined temperature; a conduit leading from said chamber, and means for supplying artificially humidified air to the conduit at a point sufficiently remote from said chamber whereby the superheated vapor in its passage

through said conduit is partially cooled, but not condensed, before the admixture of the humidified air therewith, said air supplying means including a valve for automatically controlling the admission of the humidified air to said conduit. 15

Signed at Detroit in the county of Wayne and State of Michigan, this 4th day of August A. D. 1916.

WILLIAM GRIKSCHET.
